UNITED STATES PATENT OFFICE.

MARY BEERS, OF EAST ORANGE, NEW JERSEY.

POISON-INDICATOR FOR BOTTLES.

1,223,241.

Specification of Letters Patent. Patented Apr. 17, 1917.

Application filed May 12, 1916. Serial No. 97,146.

To all whom it may concern:

Be it known that I, MARY BEERS, a citizen of the United States, residing at East Orange, in the county of Essex and State of New Jersey, have invented new and useful Improvements in Poison-Indicators for Bottles, of which the following is a specification.

This invention appertains to piston indicators for bottles and has particular application to an indicator adapted to be attached to the stopper of the bottle.

The chief characteristic of this invention resides in the provision of a device of this character which is simple and efficient in its construction and which may be readily removed from the stopper.

Another important characteristic of this invention resides in the provision of a device of this character which in addition to being an indicator for the contents of the bottle, will materially assist in removing a cork from the bottle.

Other objects of the invention will appear as the specification is read in connection with the accompanying drawings in which:—

Figure 1 is a side elevation of my device showing the same mounted within a stopper.

Fig. 2 is a perspective view of the indicator showing the same detached from the stopper.

Referring to the drawings in detail 1 designates a stopper formed of any suitable material such as cork, rubber or the like and which is provided concentrically thereof with a vertically extending opening 2, the lower end wall of the opening being formed with radially extending recesses 3, the recesses being arranged at diametrically opposite points with relation to the opening.

Referring more particularly to Fig. 2, my improved form of indicator comprises a shank 4 which is formed of any suitable material such as metal or the like and which is circular in cross section. The lower end

45 of the shank 4 is provided at diametrically opposite points with radially extending arms 5, each of which are preferably rectangular in cross section. The upper end of the shank is tapered upwardly to provide a

50 point 6, while the portion of the shank adjacent the pointed end is provided with a

transversely extending opening 7, adapted to receive a cross bar 8. This cross bar 8 is preferably circular in cross section and has the opposite ends thereof pointed as at 9. 55 When the cross bar is placed through the opening 7 formed in the shank, equal portions of the cross bar will be disposed upon opposite sides of the shank to resemble a cruciform.

Having described the specific construction of the indicator and the manner in which the stopper is formed, I will now describe the application of the indicator to the stopper.

As shown in Fig. 1, the shank of the indicator is inserted through the vertical opening formed in the stopper point first, until the radially extending arms lie within the recess 3, whereby the pointed end of the shank will be disposed above the upper face of the stopper. After having secured the shank within the stopper in the above described manner, the cross bar is then passed through the opening 7 and the shank 11, 75 thus coöperating with the radially extending arms to lock the shank upon the cork stopper.

In practice, the stopper is inserted into the bottle so as to dispose the cross bar and the 80 pointed edge of the shank exteriorly of the bottle, so that when a person attempts to remove the stopper he will be pricked by the points, thus indicating to him that the contents of the bottle are of a poisonous 85 nature. The indicator being locked upon the stopper, the stopper may be readily removed by gripping the cross bar and pulling upwardly, the radially extending arms preventing the indicator from being removed 90 from the stopper. It will thus be seen that I have provided not only a poison indicator for bottles but in addition thereto a simple and efficient means for removing stoppers from the neck of the bottle.

95 While I have described a specific form of indicator I wish it to be understood that I may make various changes in size, shape and proportion and still be within the scope of the appended claim.

100 What I claim, is:—

A poison indicator comprising a stopper

having a vertically extending opening formed therein and having a recess formed in the bottom face thereof, said recess communicating with said opening, a shank extending through said opening and having an orifice formed adjacent its upper end, arms formed on the lower end of said shank

and lying within said recess, and a cross bar extending through the orifice of said shank and detachably mounted therein, the upper 10 end of the shank and the opposite ends of the cross bar being pointed.

In testimony whereof I affix my signature.
MARY BEERS.
